UNITED STATES PATENT OFFICE.

HARRISON GARNETT, OF NORRISTOWN, PENNSYLVANIA.

BEAMING-MACHINE FOR LOOMS.

No. 806,335.

Specification of Letters Patent.

Patented Dec. 5, 1905.

Application filed May 15, 1905. Serial No. 260,422.

To all whom it may concern:

Be it known that I, HARRISON GARNETT, a citizen of the United States, residing at Norristown, in the county of Montgomery and State 5 of Pennsylvania, have invented new and useful Improvements in Beaming-Machines for Looms, of which the following is a specification.

My invention relates to beaming-machines 10 used for winding the warp for a loom from a reel onto the beam.

Heretofore the beam to be supplied with warp was driven by gearing applied at one end only, and the great torsional stress resulting 15 from the beaming operation, especially when the beam was about one-half or three-quarters filled, caused the end nearest the gearing to split or otherwise to be injured. If, as is mostly the case, the beam is supplied with a 20 ratchet or ratchets to allow for taking up or slackening off of warp when the beam is in a loom, the teeth of the ratchet-wheel are torn away, causing expenses for repair and loss of time. To avoid these objectionable features, 25 I provide means to drive the beam at both of its ends, thus avoiding the great torsional stresses by which beam and ratchets are injured entirely and obtaining the advantages of producing an evenly-wound warp, getting 30 about sixty yards more of yarn onto the beam, and facilitating the operation of beaming.

My invention consists of means for supporting a warp-beam, a removable gear at each end thereof, a shaft journaled in bearings, 35 pinions on said shaft to mesh with the said gears, and means for driving said shaft.

My invention will be more fully understood taken in connection with the accompanying drawings, forming part thereof, and in which—

40 Figure 1 is a top view of the improved beaming-machine. Fig. 2 is an end view of said machine; and Fig. 3 is a section on line 3 3 of Fig. 1, showing the beam and a ratchet.

Referring now to the drawings for a further 45 description of my invention, A represents standards with journal-boxes in which the shaft C, having the pinions c and c', and fast and loose driving-pulleys c² and c³, is journaled. Contiguous to said standards A, which 50 are bolted onto the floor, are bases a' and a'', the latter of which is provided with an open

journal-block a³, formed integral with the said base a'. The base a' is provided with a removable open journal-block a⁴, of any suitable construction—such, for instance, as is now being used with beaming-machines which are driven from one end only.

The beam B consists of the shaft b, barrel b', beam-heads b², and ratchet-wheels b³, which are secured to the barrel by means of longitudinal rods b⁴ and lugs b⁵, mortised into the wooden barrel b'. The friction-pulleys b⁶ are provided with pawls b⁷, engaging the ratchet-wheels, and are loose on the shaft b.

When it is desired to wind the warp W from a reel R onto a beam B, a gear-wheel d', having two studs d³, is slipped over the right-hand end of the shaft b, so that the studs d³ enter the holes b⁸ in the friction-pulley b⁶. The left-hand end of the shaft b is then also provided in a similar manner with a gear-wheel d, having studs d³ to enter holes b⁸ in the other friction-pulley b⁶. The beam B is then placed in the open journal-block a³ and a⁴, so that the teeth of the gears d and d' mesh with the teeth of the pinions c and c'. The ends of the warp from the reel R are then fastened to the beam B, and power is applied to the shaft C by the belt c⁴ and driving-pulley c² to give rotary motion to the beam B. A 80 guide-roll g and a presser-roll P are employed in the usual manner to maintain an even and close winding of the warp onto the beam.

Having thus fully described the nature and objects of my invention, what I claim as new, 85 and desire to secure by Letters Patent, is—

1. A beaming-machine adapted to support a warp-beam, a removable gear at each end of said beam, means for coupling said gears to said beam, and means for driving said gears, 90 substantially as and for the purposes set forth.

2. A beaming-machine adapted to support a rotating warp-beam, a removable gear at each end of said beam, means for coupling said beam to said gears, a shaft, two pinions 95 on said shaft to mesh with the removable gears of the beam, and means for driving the said shaft, substantially as and for the purposes set forth.

3. A beaming-machine adapted to support 100 a rotating warp-beam, a removable gear at each end of said beam, a ratchet at each end

of the said beam, a friction-pulley with pawl
engaging said ratchet, means for coupling said
gears with the friction-pulleys, a shaft, two
pinions on said shaft to mesh with the remov-
5 able gears of the beam, and means for driv-
ing the said shaft, substantially as and for
the purposes set forth.

In witness whereof I have hereunto set my
hand in the presence of two subscribing wit-
nesses.

HARRISON GARNETT.
